FIG.1

FIG.2

FIG.3

FIG.4

FIGURE 1 is a side view for a boom member for lifter embodying my design shown mounted on a tractor, the boom member being illustrated in an elevated substantially horizontal position;

FIGURE 2 is a plan view of the boom member shown in FIGURE 1;

FIGURE 3 is a front view looking at the boom member from the righthand end of FIGURE 1; and

FIGURE 4 is a rear view looking at the boom member from the lefthand end of FIGURE 1.

The bottom of the boom member is substantially plain.

The dotted line showing in the drawing is for illustrative purposes only.

I claim:

The ornamental design for a boom member for lifter, substantially as shown and described.
